ROTARY WATER PUMP

John E. Hagstrom, Englishtown, N. J.

Application December 21, 1942, Serial No. 469,690

2 Claims. (Cl. 103—137)

This invention relates to rotary water pumps and has for an object to provide vanes for the rotor spring pressed away from each other to maintain leather backing strips in tight engagement with the eccentric wall of the stator so that the vanes will be actuated by the eccentric wall to suck liquid from the inlet side of the pump casing and discharge it from the outlet side of the pump casing when the rotor is driven at high speed, without air locks being formed in the casing and without back pressure, which ordinarily in centrifugal or rotary pumps reduces the effectiveness of the pump and increases wear on the moving parts.

A further object is to provide apparatus of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of a pump constructed in accordance with the invention and showing the electric motor for driving the pump and pressure switch, the latter two members being conventional.

Figure 2 is a cross sectional view of the pump with parts in elevation.

Figure 3 is a cross sectional view of the pump with one of the housing plates removed, taken in a plane at a right angle to the plane of the section of Figure 2.

Figure 4 is a detail perspective view of the rotor and stub shafts for mounting the rotor in the housing.

Figure 5 is a detail perspective view of the holder member of one of the vanes.

Figure 6 is a detail perspective view of the spring carrier which is disposed between both vanes.

Figure 7 is a side elevation of the rotor showing the gudgeons which connect the two sections of the rotor together.

Referring now to the drawing in which like characters of reference designate similar parts in the various views, 10 designates the pump hous-

ing, the same being substantially rectangular in contour, see Figure 3, and closed at the sides by side plates 11, secured to the housing by bolts 12, see Figure 2.

5 A cylindrical stator 13 is mounted transversely in the pump housing. The ends of the stator are closed by the side plates 11 and the stator is held in place by lugs 14, see Figure 2, which projects inwardly from the housing and have rounded extreme ends conforming to the curvature of the outer surface of the stator. The stator is provided in the bottom with inlet ports 15 and is provided in the top with outlet ports 16, these ports extending throughout an area of the stator, see Figure 3.

An outlet pipe 17 is threadedly engaged through the pump housing at the top thereof, as shown at 18, and projects into the housing to a point spaced from the stator so that an air space or cushion 19 exists around the outlet pipe in the upper end of the housing.

An inlet pipe 20 is threadedly engaged through the bottom of the housing, as shown at 21, and the pipe terminates at the inner face of the housing so that a liquid space 22 exists in the housing below the inlet ports 15 of the stator. A priming pipe 23 enters one side of the pump housing. The priming pipe communicates with the chamber 22 in the bottom of the housing.

30 An important feature of the invention is the rotor and parts carried thereby. As best shown in Figure 4, the rotor 24 comprises two semi-cylindrical sections 25 having their flat sides spaced from each other. The sections are secured together by aligned gudgeons 26 and 27 which enter recesses in the ends of the sections and are welded or otherwise rigidly secured to the sections. The gudgeon 26 is hollow and forms a shaft for rotating the rotor. The gudgeon is provided with a tapered inner end 28 which enters a correspondingly shaped recess formed in the sections. The gudgeon 27 is provided on its inner end with a disk 29 which is countersunk in a similarly shaped recess in the opposite end of sections. The tapered end 28 of the gudgeon 26 and the disk 29 of the gudgeon 27 are,

40 as heretofore stated, welded or otherwise secured to the walls of their respective recesses to secure the sections of the rotor together as a unit.

The gudgeons 26 and 27 are mounted in respective bearing openings 30 and 31 in the side plates 11 of the pump housing, see Figure 2. The bearing openings are disposed eccentric to the axis 55 of the cylindrical stator 13 so that the rotor is

eccentrically mounted within the stator and engages the inner wall of the stator throughout a limited area of the outer circumferential face of the stator, see Figure 3.

A pair of similar vanes 32 are slidably mounted to move endwise in the spaces between the sections 25 of the rotor. Each vane is substantially H-shaped in cross section and extends at the outer portion substantially the entire length of the rotor so as to engage the inner faces of the side plates 11 of the pump housing, see Figure 2. The inner portion of the vane is cut away, as shown at 33 and 34, see Figure 5, to receive the tapered end 28 of the gudgeon 26 and the disk 29 of the gudgeon 27, during endwise reciprocation of the vane.

A leather wear strip 35, of substantially rectangular longitudinal section and cross section, is snugly fitted in the outer portion of the vane and has wiping engagement with the inner surface of the stator when the rotor is rotated.

A spring carrier 36, see Figure 6, is interposed between both vanes and is in the form of a solid block of material having a pair of spaced openings 37. A pair of helical springs, one of which is shown at 38 in Figure 3, is disposed in the openings 37 and project at both ends into the confronting inner ends of the vanes 32. The springs constantly tend to urge the vanes away from each other so that good wiping engagement is maintained between the leather members 35 and the inner surfaces of the stator during rotation of the rotor, and thus leakage past the vanes is prevented.

In operation, when the rotor is rotated in the direction of the arrow, shown at 39 in Figure 3, liquid will be forced ahead of each vane as the vane begins to travel clockwise from the contacting surfaces of the rotor and stator, and as the vane moves outwardly during rotation of the rotor, the liquid will be forced ahead of the vane out of the outlet openings 16. The companion vane meanwhile will be moved inwardly by contact with the inner surface of the stator as the first named vane is moved outwardly to begin its working stroke when it arrives at a point slightly beyond the contacting surface of the rotor and the stator.

A grease connection 40, see Figure 2, is threadedly engaged with one of the side plates 11 and communicates with an axial opening 41 formed in the gudgeon 27.

An air valve connection 42, of conventional construction, see Figure 3, is secured to the pump housing and communicates with the liquid chamber 22 in the bottom of the housing.

A pair of set screws 43 are engaged through the

pump housing and through the lugs 14. The set screws have reduced tips 44 which are engaged in openings 45 in the stator to rigidly secure the stator against dislodgment.

5 The pump is preferably driven by an electric motor 46, see Figure 1, which is coupled, as shown at 47, to a shaft 48 which extends through a bearing sleeve 49, see Figure 2, carried by one of the side plates 11 of the pump housing and has the inner end fixed to the gudgeon 26 which, as heretofore stated, forms means for rotating the rotor. A conventional grease cup 50 is secured to the bearing sleeve 49.

10 Preferably, an expansion chamber 51, see Figure 1, is secured to the outlet pipe 17 of the pump housing to regulate a pressure switch 52 which controls the motor 46 to speed up or slow down according to predetermined pressure in the chamber 51.

15 From the above description it is thought that the construction and operation of the invention will be fully understood without further explanation.

20 What is claimed is:

25 1. In a pump, a housing, a cylindrical stator mounted in the housing having inlet and outlet openings in opposed sides thereof, a cylindrical rotor mounted eccentrically in the stator and provided with a longitudinal through slot, an elongated block fitted centrally within the slot of the rotor having spaced through bores, a vane slidably fitted in each outer portion of the slot, coiled compression springs extending through the bores in the block and bearing against the vanes to resiliently thrust the same against the interior 30 of the stator, and inlet pipe connecting with the housing and opening adjacent the inlet openings of the stator, and an outlet pipe projecting into the housing having its inner open end disposed 35 adjacent the outlet openings in the stator.

40 2. In a pump, a rotor including a pair of complementary sections spaced transversely to provide a longitudinal through slot therebetween, a flat elongated vane mounted longitudinally in each outer portion of the slot, said vane having a longitudinal groove in its outer portion and a longitudinal groove in its inner portion, an elongated block having longitudinally spaced bores therein fitted in the intermediate portion of the rotor slot, the inner grooved portions of the vanes being slidably fitted over the opposed side portions of said block, compression springs extended through the bores of the block and bearing against the inner edges of the vanes to resiliently 45 thrust the vanes outwardly, and a wear strip fitted in the outer groove of each of the vanes.

50 JOHN R. HAGSTROM.
